UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

LAST.

1,112,402.

Specification of Letters Patent. Patented Sept. 29, 1914.

Application filed March 9, 1909. Serial No. 482,390.

To all whom it may concern:

Be it known that I, HARRIE A. BALLARD, of Boston, in the county of Suffolk and State of Massachusetts, have invented certain new 5 and useful Improvements in Lasts, of which the following is a specification.

This invention relates to lasts and its object is to provide a last of inexpensive construction comprising a heel-part and a fore-part 10 which are adapted to slide one with relation to the other so that the last may be shortened.

In carrying out the invention, the two parts of the last are formed with complementary tongue and groove portions which are adapted to slide upon each other and hold the two parts together with sufficient 15 rigidity to withstand strains of ordinary usage. The tongue and groove portions are so formed as to be invisible except upon the sole of the last or when it is open or in its shortened state. By so forming the last, the appearance of the instep portion is not marred except by a single dividing line. In 20 forming the tongue and groove it is preferable that the groove be begun at the sole and continued upwardly in an inclined plane toward but not quite to the instep. In order to compensate for the remaining stock left 25 between the end of the groove and the instep on one part of the last, the tongue portion on the other part is by necessity terminated at a suitable distance from the instep. Suitable locking mechanism is provided for locking 30 the last in its working condition and for preventing separation of the two parts when one is moved relatively to the other.

One form of construction in which the invention may be embodied is illustrated upon 40 the accompanying drawings of which—

Figure 1 is a side elevation with a portion thereof in section. Fig. 2 is a side elevation of the toe-part. Fig. 3 is a side elevation partly in section of the heel-part. Fig. 4 is a 45 top view of the toe-part on a line parallel to the tongue formed thereon. Fig. 5 is a section on line 5—5 of Fig. 3. Fig. 6 is an elevation similar to Fig. 1 showing the last in its shortened condition.

50 The same reference characters indicate the same parts wherever they occur.

On the drawings, the forepart of the last is indicated at 10 and the heel-part at 11, and they are so formed as to abut against

each other on a line inclined to a transverse 55 perpendicular plane. The abutting faces, which are visible from the exterior, are indicated at 12 and 13, and preferably extend from that part of the sole at the rear of the arch to a point about midway of the instep. 60 In this embodiment of the invention, a tongue 14 of T-shape cross section is formed on the inclined abutting face 12 of the fore-part, and a corresponding groove 15 of T-shape cross section is formed in the abutting 65 portion of the heel-part. The tongue extends from the sole line part way toward the instep and terminates abruptly, while the groove 15 likewise starts at the sole line and extends part way toward the instep. The 70 forepart and heel-part are assembled by placing the sole line of the heel-part at the upper end of the tongue 14 with the abutting faces 12 and 13 in contact with each other, and by sliding the two parts in opposite directions so as to insert the tongue in the 75 groove. When the two parts are in the position shown by Fig. 1, the tongue and groove connection is visible only on the sole portion and the only mark of division visible in the 80 instep is the line of the abutting faces 12 and 13.

A suitable locking device is shown for locking the two parts in the position shown by Fig. 1 and for preventing removal of one 85 part from the other when the tongue is moved longitudinally in the groove. The locking mechanism comprises a spring follower 16 installed in one part and confronting faces α afforded by an aperture 17 90 formed in the other part. The follower 16 is contained in a socket 18 and has a reduced stem 19 which extends through an aperture in the inner end of the socket 18 and which is provided with a head 20 at its 95 extremity. A helical spring surrounding the stem 19 is compressed between the inner end of the socket 18 and the larger portion of the follower 16 and tends to project the follower toward the other part of the last. 100 The aperture 17 is provided with a metal bushing 21.

In order to retract the follower 16 to unlock the last, a straight tool may be inserted in the outer end of the aperture 17. It is 105 preferable that the spring follower 16 be installed in the forepart and the aperture 17 formed in the heel-part, and that a socket

22 be formed in the back wall of the groove 15 so as to present an abrupt shoulder 23 extending transversely of the groove. When the follower 16 is retracted and the heel-part 5 moved to the position shown by Fig. 6, the follower may enter the socket 22 so as to engage the shoulder 23 and so limit the sliding movement of the heel-part. If the wall of the socket 22 between the shoulder 23 and 10 the aperture 17 is inclined as indicated at 24, it is adapted to retract the follower 16 when the heel-part is moved to its working position without the use of a tool.

Having thus explained the nature of my 15 said invention and described a way of constructing and using the same, although without attempting to set forth all of the forms in which it may be made or all of the modes 20 of its use, I declare that what I claim is:—

20 1. A last comprising a forepart and a heel-part having abutting faces, the abutting portion of one part having an undercut groove of uniform width, a portion of the other part being in the form of a flanged tongue adapted to slide in said groove; and a retractable stop member projecting from 25 said tongue, the last part having said groove being provided with faces adapted to be engaged by said stop member to limit relative 30 movement in both directions of the last parts and with an additional face for confining said stop member so as to prevent all relative movement, the last parts being separable when said stop member is retracted.

35 2. A last comprising a forepart and a heel-part having abutting faces, the abutting portion of one part having an undercut groove of uniform width, and a portion of the other part being formed with a tongue 40 flanged on its sides to fit and slide in said groove; and a stop member projecting from the abutting portion of one of said parts, the other of said parts having an elongated recess arranged to receive said stop member 45 and permit lateral movement of the same therein so that said last parts may slide relatively to each other, said recessed part having a stop face at one end of said recess adapted to coact with said stop member to

limit such relative movement of the last 50 parts.

3. A last comprising a forepart and a heel-part having abutting faces, the abutting portion of one part having an undercut groove of uniform width, and a portion 55 of the other part being formed to fit and slide in said groove; and a stop member projecting from the abutting portion of one of said parts, the other of said parts having an elongated recess arranged to receive said 60 stop member and permit lateral movement of the same therein so that said last parts may slide relatively to each other, said recessed part having a stop face at one end of said recess adapted to coact with the side of 65 said stop member, and a second recess at the opposite end of said elongated recess, said second recess having confronting faces arranged to coact with opposite sides of said stop member to confine said stop member 70 against all lateral movement.

4. A last comprising a forepart and a heel-part having abutting faces, the abutting portion of one part having an undercut groove of uniform width, and a portion 75 of the other part being formed to fit and slide in said groove; and a stop member projecting from the abutting portion of one of said parts, the other of said parts having two confronting stop faces arranged to 80 coact with opposite sides of said stop member to limit relative sliding movement of said last parts, said stop member being movable laterally between said stop faces, a third stop face between said two stop faces and 85 confronting one of said two stop faces to confine said stop member against lateral movement, and an inclined face arranged to coact with the end of said stop member to move said stop member endwise beyond 90 said third stop face.

In testimony whereof I have affixed my signature, in presence of two witnesses.

HARRIE A. BALLARD.
